UNITED STATES PATENT OFFICE.

MAX KRAUT, OF SAN FRANCISCO, CALIFORNIA.

REAGENT FEEDER.

Application filed June 18, 1928. Serial No. 286,472.

This invention relates to improvements in reagent feeding devices for flotation apparatus.

The principal object is to provide a simple and efficient means for accurately feeding the desired amount of oils or other reagents to the liquid mineralized pulp. Another object is to provide an apparatus having means for quickly and accurately varying the feeding of the reagent to the pulp, and also to provide a feeding apparatus which will combine highest efficiency at little cost, and which is simple in construction and economical in operation.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein—

Fig. 1 is a view in side elevation, partly in section, of the preferred embodiment of my invention.

Fig. 2 is a view in top plan.

Fig. 3 is a view in front end elevation.

In the drawings, wherein like characters of reference designate corresponding parts, 1 indicates a container for a body of oil or reagent to be fed or delivered to mineralized pulp for treatment in a flotation or other apparatus.

In bearings 2 carried by the upper edges of the side walls of the container 1, is a shaft 3 mounting a reagent pick-up wheel or elevator 4, having a relatively broad face 5, the latter depending into the reagent body on the rotation of the wheel. The face of the wheel or elevator 4 is circumferentially grooved at 6, to afford a greater pick-up area than if the same were smooth. The shaft 3 has gear connection at 7 with the power shaft 8 rotatable in bearings 9 and carrying a power wheel 10 driven from any suitable power source.

Supported above the container 1, preferably at the forward end of the container 1, is a reservoir 11 having an inlet 12 and a suit-

able reagent outlet 13, the latter being illustrated as controlled by a needle valve 14. A suitable pick-up trough 15 is positioned with one end cooperating with the grooved faces 60 of the elevator 4 to remove the reagent adhering thereto, and the other end extending downwardly toward the reservoir inlet 12 into which it discharges. The trough is provided with a removable separating screen 16, 65 through which the reagent passes prior to entering the reservoir 11. The speed of the pick-up wheel or elevator 4 and the area of its surface is such that the material elevated thereby and deposited in the reservoir 11 is greater than the capacity of the reservoir outlet 13, so that the fluid level within the reservoir will, at all times, be maintained to drain through the overflow pipe 17 within the reservoir and discharge into the container 1. 70

Mounted at the end of the container 1 is a transversely disposed oscillating shaft 18 carrying a mounting block 19 in which is longitudinally adjustable an open ended tubular reagent conveyer 20, disposed at right 80 angles to the shaft, as in Fig. 1.

The conveyer 20 is normally disposed with its discharge end in a plane below its receiving end, and at a point projecting beyond the forward end wall of the container 1. 85

To the end of shaft 18 is secured an angle lever 22, weighted at 23, with its end resting on the end 24 of a relatively long lever 25, fulcrumed to the side of container 1, at 26. Lever 25 carries pin 27 extending laterally 90 therefrom in parallel spaced relation beneath the extension 28 of shaft 3.

Mounted to ride longitudinally of pin 27 is a shoe 29 on the end of an operating lever 30 fulcrumed at 31 to block 32 and adapted for longitudinal movement on an adjusting screw 33 disposed parallel with shaft extension 28, screw 33 carrying an operating wheel 34. Above the shoe 29 the lever 30 carries an idler 35 which bears on the periphery of a cylinder 36 carried by and rotatable with the shaft extension 28. Cylinder 36 has a portion of its periphery cut away or recessed at 37, one edge of the recess or cut away portion being disposed spirally of the cylinder, 100 as at 38, and the other being longitudinally disposed, as at 39.

In operation, the continuous rotation of the elevator 4 maintains the fluid level in reservoir 11 at a point overflowing pipe 17. 110 The needle valve is adjusted to permit the desired quantity to flow from the reservoir in

a given time. The adjusting wheel is rotated to move block 32 longitudinally of screw 33, and position idler 35 at the desired point longitudinally of cylinder 36.

5 It will be observed that when the recessed portion 37 of the cylinder is presented to idler 35, the receiving end of the tubular conveyer 20 is under the stream flow from the discharge 13 of reservoir 11, directing the reagent from its path of normal gravity flow. When the rotation of the cylinder 36 removes the recessed portion from the idler, the conveyor 20 is moved from without the path of the stream flow from reservoir 11 and the fluid 10 discharging from the outlet 13 returns to the container 1.

By forming one edge of the cylinder recess spirally of the cylinder, and the other edge longitudinally disposed, the position of the 15 idler 35 longitudinally of the cylinder controls the timing of pivot of conveyor 20.

I claim:—

1. In a reagent feeder, a reservoir provided with a continuous discharge and an overflow, 20 means for delivering to the reservoir a fluid reagent in a greater quantity than the capacity of the discharge, conveying means movable at timed intervals to intersect the continuous discharge of reagent from the reservoir and to direct the same from its usual path, and means for varying the timing of the conveying means into and from the flow of discharge of the reagent.

2. In a reagent feeder, a reservoir provided with a continuous gravity discharge for the fluid content therein and an overflow, means for delivering to the reservoir a fluid reagent in a greater quantity than the capacity of the discharge, a tiltably mounted conveying means positioned with one end movable to intersect the continuous discharge of reagent from the reservoir to direct the same from its path of gravity flow, means for pivoting said conveying means, and means for 40 varying the timing of the pivot of said conveying means.

3. In a reagent feeder, a reservoir provided with a continuous gravity discharge for the fluid content therein and an overflow, means 50 for delivering to the reservoir a fluid reagent in a greater quantity than the capacity of the discharge, a tiltably mounted conveying means positioned with one end movable to intersect the continuous discharge of reagent 55 from the reservoir to direct the same from its

path of gravity flow, a lever associated with the conveying means, and means for pivoting the lever including a rotatable cylinder formed on its surface with a longitudinal depression, one edge of which is disposed spirally of the cylinder surface, and an idler associated with the lever and adjustable longitudinally of the cylinder.

4. In a reagent feeder, a main body of fluid reagent, an endless elevator dipping thereto for continuously removing reagent therefrom, a reservoir elevated from the main body of reagent provided with an inlet, a valve controlled continuous discharge of a lesser capacity than the elevating capacity of the 60 elevator, and an overflow discharging into the main fluid body; means for removing the fluid reagent from the elevator and for delivering it into the reservoir, conveying means movable for intersecting the continuous reagent discharge from the reservoir at predetermined intervals, and means for varying the timing of operation of the conveying means.

5. In a reagent feeder, a container for a main body of fluid reagent, a pick-up wheel rotatably mounted and dipping into the body of fluid reagent, means for operating the pick-up wheel for elevating the reagent from the container, said pick-up wheel formed on 80 its periphery with a plurality of circumferential channels, a reservoir elevated above the container and provided with a reagent inlet, a valve controlled continuous reagent discharge of a lesser capacity than the elevating 85 capacity of the pick-up wheel, said reservoir provided with an overflow discharging into the container, a trough coacting at one end with the periphery of the pick-up wheel to remove the reagent from the surface thereof and convey the same to the reagent inlet of the reservoir, a pivotally mounted conveying trough movable at one end into the continuous discharge of reagent from the reservoir to receive and direct the same from its 90 path of gravity flow, and means for tilting the pivoted conveyer means and including a cylinder rotatably mounted and provided on its surface with a longitudinal depression, one wall of which is disposed spirally of the 95 cylinder.

In testimony whereof I have signed my name to this specification.

MAX KRAUT.
